UNITED STATES PATENT OFFICE.

JOHN ROBERT HOBBS, OF LONDON, ENGLAND.

TOOL FOR GRINDING INTERNAL CYLINDRICAL SURFACES.

1,393,625.

Specification of Letters Patent. Patented Oct. 11, 1921.

Application filed June 15, 1920. Serial No. 389,192.

To all whom it may concern:

Be it known that I, JOHN ROBERT HOBBS, a British subject, residing at 21 Buller road, Kensal Rise, London, England, have invented certain new and useful Improvements in Tools for Grinding Internal Cylindrical Surfaces, of which the following is a specification.

This invention relates to a new or improved tool primarily intended for grinding the cylinders of internal combustion engines either for the purpose of removing scores or ridges, or in connection with the fitting of over-size pistons. The invention is, however, applicable generally for grinding internal cylindrical surfaces.

The invention is illustrated in the accompanying drawing in which Figure 1 shows an elevation of the assembled tool, Fig. 2 an underside view of Fig. 1, Fig. 3 is an elevation of the cage, Fig. 4 is an elevation of the cutting stone, Fig. 5 is a plan of the cage, Fig. 6 is a plan of the cutting stone, Fig. 7 is a plan and Fig. 8 is an edge view 25 of the retaining washer.

According to the preferred form of the invention, the improved tool comprises a central body 1 of solid material, generally cylindrical in shape, but provided with two 30 or more dove-tailed slots 2 of which three are shown in dotted lines in Fig. 2, the slots being arranged axially the whole length of the cylinder. The body is centrally bored and the lower face is provided with an integral circular flange 3, Fig. 2.

The dove-tailed slots are adapted to house correspondingly formed cages, 4, Figs. 3 and 5, each adapted to receive a carborundum or similar cutting stone 5, Figs. 4 and 6, the 40 stones being urged outwardly by springs 6 partly housed in sockets 7 in the cages.

The walls 8 of the cages are provided with slots 9 forming inturned flanges 10 adapted to engage with flanges 11 formed on the 45 stones; both flanges extend to the upper end of the cages but are interrupted close to the lower end to form a stop for the retention of the stones. The cages are shouldered at the lower end as shown in order to receive 50 a washer 12, Figs. 7 and 8 which registers with and is attached to the lower end of the body by screws and forms an abutment for the cages. The body is mounted on a central spindle 13, of which the head 14 55 is shown in Fig. 2 seated within the flange

3, and is locked thereon by means of a wing nut 15 and washer 16.

It is apparent from the construction above described that the grinding stones extend the full length of the body and that thereby 60 the grinding action may readily reach the extreme end of the cylinder, and furthermore the coöperation of the cages and body is such as to permit the association with the body of cages of different sizes, as may 65 be necessary in use with cylinders of different bores.

In use the tool may be operated either by a hand brace or drill, or set up in a lathe or drilling machine. One convenient 70 mode of operation consists in mounting it in a pillar drilling-machine the cylinder being bolted to a stand.

It is intended to provide with each tool cages of varying sizes to suit cylinders of 75 varying diameters outside the limits to which the range of adjustment provided by the springs 6 in the form shown is accommodated.

I claim:

1. A tool for grinding internal cylindrical surfaces, comprising a body, cages held in ways formed in the body, an abutment member secured to the lower end of the body, the cages being recessed to receive the abutment member, and a grinding stone slidably held in each cage and normally projected toward the article being ground. 80

2. A tool for grinding internal cylindrical surfaces, comprising a body, cages held in ways formed in the body, an abutment member secured to the lower end of the body, the cages being recessed to receive the abutment member, a grinding stone for each cage having projections, the cages having 85 flanges to coöperate with said projections to limit movement of the stones in one direction, and springs bearing between cages and stones to project the stones toward the article being ground. 90

3. A tool for grinding internal cylindrical surfaces, comprising a body, cages held in ways formed in the body, an abutment member secured to the lower end of the body, the cages being recessed to receive the 105 abutment member, and a grinding stone slidably held in each cage and normally projected toward the article being ground, a spindle having a head housed within an opening in said abutment member, and 110

means carried by said spindle and body to secure the spindle in fixed relation to the body.

4. A tool for grinding internal cylindrical surfaces comprising a body formed with dove-tailed ways extending throughout the length thereof, cages arranged for coöperation with the body and each comprising a projection to fit within a dove-tailed way in the body, walls extending from the projection to provide a receiving member, and a grinding stone arranged in the receiving member and adapted for movement radially of the body.

15 5. A tool for grinding internal cylindrical surfaces comprising a body, cages held in ways formed in the body, an abutment member secured to the lower end of the body, the cages being recessed to receive said member and beyond the recess extending to the extreme lower end of the tool, and a grinding stone removably supported in each cage, the said stone being of the full length of the cage.

20 6. A tool for grinding internal cylindrical surfaces, comprising a body formed with vertically extending dove-tailed ways, cages having parts to coöperate with said ways and hollow extensions from said parts, the parts making the ways being of less length than the hollow extensions to provide recesses at the rear of the cages, an abutment secured upon the lower end of the body and fitting in said recesses to hold the cages in place at the lower end, removable means to secure the cages with relation to the body at the upper end, and a grinding stone mounted in each hollow extension of each cage and movable radially with respect to the body.

35 7. A tool for grinding internal cylindrical

surfaces, comprising a body formed with vertically extending dove-tailed ways, cages having parts to coöperate with said ways and hollow extensions from said parts, the parts making the ways being of less length than the hollow extensions to provide recesses at the rear of the cages, an abutment secured upon the lower end of the body and fitting in said recesses to hold the cages in place at the lower end, removable means to secure the cages with relation to the body at the upper end, and a grinding stone mounted in each hollow extension of each cage and movable radially with respect to the body, said grinding stones being of the full length of the hollow extensions of the cages and equaling the full length of the body and abutment.

8. A tool for grinding internal cylindrical surfaces, comprising a body formed with vertically extending dove-tailed ways, cages having parts to coöperate with said ways and hollow extensions from said parts, the parts making the ways being of less length than the hollow extensions to provide recesses at the rear of the cages, an abutment secured upon the lower end of the body and fitting in said recesses to hold the cages in place at the lower end, removable means to secure the cages with relation to the body at the upper end, and a grinding stone mounted in each hollow extension of each cage and movable radially with respect to the body, the hollow extension of each cage being formed with recesses closed at the outer ends, and the grinding stones having ribs to slidably seat in said recesses, and springs to normally project the grinding stones to the limits of said recesses.

In testimony whereof I affix my signature.
JOHN ROBERT HOBBS.
